SIGHT FOR FIREARMS

Carl G. Swebilius, New Haven, Conn.

Application March 12, 1936, Serial No. 68,438

4 Claims. (Cl. 33—56)

This invention relates to sights for firearms and more especially to a sight for automatic pistols.

An object of the invention is a firearm rear sight which is easily and quickly adjustable both for windage and for elevation.

According to the invention, the rear sight is mounted on the firearm both for swinging movement longitudinally of the firearm and for bodily movement transverse thereof. The sight is locked in any desired position of adjustment by two spring-pressed plungers and the pressure applied to the plungers is regulated by adjustment of a single screw. To effect adjustment of the sight, it is necessary merely to rotate the screw to reduce the pressure applied to the plungers, move the sight into its desired position of adjustment and then adjust the screw to restore the required holding pressure on the plungers.

Other objects, novel features and advantages of this invention will become apparent from the following specification and accompanying drawing, wherein:

Fig. 1 is a side elevation of a pistol equipped with a sight embodying the invention;

Fig. 2 is a plan view thereof;

Fig. 3 is an enlarged section on the line 3—3 of Fig. 2, and

Fig. 4 is an enlarged section on the line 4—4 of Fig. 1.

The sight is herein disclosed as applied to an automatic pistol 10 having a sliding breech bolt 11. Near the rear end of the breech bolt is provided a transverse groove 12 which is somewhat more than semi-circular in cross-section. In this groove is arranged a cylindrical head 13 from which extends radially a plate 14 having a slot 15, the head and plate together constituting the sight. The sight is thus mounted on the breech bolt for

swinging movement longitudinally of the breech bolt and for bodily movement transversely of the breech bolt. A bore 16 extends longitudinally of the breech bolt and traverses the groove 12. In the front end of the bore 16 is arranged a plunger 17 having a pointed end engageable with the head 13. A spring 18 urges the plunger 17 toward the head 13 which is provided with a plurality of grooves or serrations 19 for receiving the edge of the plunger 17. In the rear end of the bore 16

is provided a second plunger 19 with a pointed end engageable with the head 13. A spring 21 interposed between the plunger 20 and a screw 22 threaded into the rear end of the bore 16 urges the plunger 19 toward the head 13 which is provided with transverse grooves or serrations 23

into which the pointed edge of the plunger 20 is receivable.

The engagement of the edge of the plunger 17 with the serrations 19 holds the sight in any lateral position of adjustment while the engagement of the pointed edge of the plunger 20 in the serrations 23 holds the sight in any position of elevation adjustment. The pressure exerted by the springs 18 and 21 is regulated by the screw 22 which can be screwed into the bore sufficiently that the applied pressure holds the sight firmly in any position of adjustment. In order to change the adjustment of the sight the screw 22 is screwed outwardly of the bore 16 until the pressure applied to the sight by the springs 18 and 21 is sufficiently reduced to permit easy swinging and/or lateral movement thereof. The sight is then moved to the desired position of adjustment and the screw 22 again screwed in to increase the pressure applied to the head 13 until the sight is again locked in position.

Adjustment of the sight can easily and quickly be effected. Adjustment for windage is made by transverse movement of the sight while adjustment for elevation is made by swinging movement of the sight, as such swinging movement changes the vertical position of the bottom of the slot 15. The usual front sight 24 is provided at the front end of the barrel for cooperation with the rear sight in the usual manner.

While the invention has been disclosed as applied to an automatic pistol, it is to be understood that the sight herein described may be used on other types of firearms as desired. Furthermore, it is to be understood that various modifications may be made in the structure herein described without in any way departing from the spirit of the invention as defined in the appended claims.

I claim:

1. In a firearm, a sight having a cylindrical head slidably and rotatably mounted in a groove in the firearm, a pair of plungers in a bore traversing said groove, said plungers being on opposite sides of said head, a spring pressing each plunger into engagement with said head, means on said head whereby said plunger may lock the same in adjusted positions, and a screw threaded into said bore for adjusting the pressure applied by said springs to said plungers.

2. In a firearm, a sight having a cylindrical head slidably and rotatably mounted in a groove in the firearm, a pair of plungers in a bore traversing said groove and said plungers being on opposite sides of said head, means on said head whereby said plungers may lock the same in ad-

- justed positions, a spring seated in said bore and pressing one plunger into engagement with said head, a second spring in said bore for pressing the second plunger into engagement with said head and a screw threaded into said bore for engagement with said second spring to vary the pressure applied thereby.
3. In a firearm, a sight having a cylindrical head received in a groove in the firearm, a pair of plungers in a bore traversing said groove, said plungers being on opposite sides of said head, a spring pressing each plunger into engagement with said head, a screw threaded into said bore for adjusting the pressure applied by said springs to said plungers, said plungers having knife edge ends and said head having a series of horizontal serrations engageable by one plunger and a series of vertical serrations engageable by the other plunger.
4. In a firearm, a sight having a cylindrical head received in a groove in the firearm, a pair of plungers in a bore traversing said groove and said plungers being on opposite sides of said head, a spring seated in said bore and pressing one plunger into engagement with said head, a second spring in said bore for pressing the second plunger into engagement with said head, a screw threaded into said bore for engagement with said second spring to vary the pressure applied thereto, said plungers having knife edge ends and said head having a series of horizontal serrations engageable by one plunger and a series of vertical serrations engageable by the other plunger.

CARL G. SWEBILIUS.
